[57] **ABSTRACT**

A phosphorothioamide having the formula,

wherein R_1 is an alkyl having up to four carbon atoms, R_2 and R_3 are individually a hydrogen atom, an alkyl having up to 10 carbon atoms, a cycloalkyl having up to 6 carbon atoms, a phenyl, an aralkyl having up to eight carbon atoms or an alkenyl having up to five carbon atoms, R_4 and R_5 are each alkyl having up to five carbon atoms, and X is an oxygen or sulfur atom, which may be effectively used as an insecticidal, acaricidal and fungicidal composition.

The phosphorothioamide is prepared by (1) dealkylating a thionophosphoric acid amide having the formula,

wherein R_1 , R_2 and R_3 are as defined above, with an alkali hydrosulfide, to prepare a phosphate having the formula,

(2) condensing the thus obtained phosphate with a halogen compound having the formula,

wherein Hal represents a halogen atom, and R_4 , R_5 and X are as defined above.

9 Claims, No Drawings

(ALKLLTHIO ETHYL) PHOSPHOROTHIOAMIDATE

This invention relates to phosphorothioamidate, a process for preparing the same and a novel systemic insecticidal, acaricidal and fungicidal composition, characterized by containing the same as an active ingredient, which is effective for the control of injurious insects and plant diseases.

More particularly, the invention pertains to (1) a novel phosphorothioamidate represented by the formula,

wherein R_1 is an alkyl having up to four carbon atoms, R_2 and R_3 are individually hydrogen atom, an alkyl having up to 10 carbon atoms, a cycloalkyl having up to six carbon atoms, a phenyl, an aralkyl having up to eight carbon atoms or an alkenyl having up to five carbon atoms, R_4 and R_5 are individually an alkyl having up to five carbon atoms, and X is an oxygen or sulfur atom, and to (2) a process for preparing the novel phosphorothioamidate, characterized by dealkylating a thionoamidate represented by the formula,

wherein R_1 , R_2 and R_3 are as defined above, with an alkali hydrosulfide represented by the formula,

(III)

wherein M is an alkali metal atom, to obtain a phosphate represented by the formula,

wherein R_1 , R_2 , R_3 and M are as defined above, and then condensing said phosphate with a halogen compound represented by the formula,

(V)

wherein Hal represents a halogen atom, and R_4 , R_5 and X are as defined above.

In the process of the present invention, when the thionoamidate represented by the formula,

wherein R_1 is as defined above, is used, the dealkylating reaction may be conducted by using an alkali hydroxide represented by the formula,

wherein M is as defined above.

The thionoamidate represented by the formula (II) may be obtained by the method described in *Z. obšč. chim.* 25 828.

The present compounds represented by the formula (I) are particularly suitable for the control of injurious insects, and can most effectively exterminate planthoppers, mites, stem borers, scales and nematodes as well as injurious insect belonging to Arthropoda such as Lepidoptera, Diptera, Coleoptera and Hemiptera. What is to be worthy of special mention is that the present compounds are excellent not only in contact and stomach insecticidal action but also in systemic insecticidal action and have prominent acaricidal actions on mites

which are resistant to conventional chemicals. Further, the present compounds have such fungicidal actions as to be effectively applicable to various plant diseases. They can control rice blast more effectively than commercially available chemicals and show, in addition, prominent effects of controlling rice *Helminthosporium* leaf spot, rice sheath blight and the like. The present compounds have excellent characteristics, which have never been seen heretofore, in that they can show insecticidal and acaricidal actions simultaneously with fungicidal actions. Thus, the present compounds are markedly useful as agricultural insecticides, acaricides and fungicides.

The present invention also relates to (3) a novel, systemic insecticidal, acaricidal and fungicidal composition, characterized by containing as an active ingredient at least one phosphorothioamidate represented by the formula (I).

The present compounds are synthesized in the following manner:

An alkali hydroxide, e.g. sodium hydroxide or potassium hydroxide, is dissolved in a suitable solvent, e.g. an alcohol such as methanol, ethanol or methyl cellosolve, water, *N,N*-dimethylformamide or dimethyl sulfoxide, and the solution is saturated with hydrogen sulfide to obtain a solution of an alkali hydrosulfide represented by the formula (III). To this solution is added the thionoamidate represented by the formula (II), and the mixture is heated with stirring to dealkylate said thionoamidate, whereby a crystalline or viscous liquid phosphate represented by the formula (IV) is obtained. The thus obtained phosphate is isolated and is dissolved in a suitable solvent, e.g. an alcohol such as methyl alcohol or ethyl alcohol, a ketone such as methylethylketone or acetone, or water, and is then condensed with a halogen compound represented by the formula (V), whereby a desired phosphorothioamidate represented by the formula (I) can be easily obtained in a high yield. In some cases, the phosphate may be condensed without being isolated or without being dissolved in a solvent.

The temperature employed in the dealkylation reaction varies depending on the kind of starting materials and solvent employed, but may be the reflux temperature of the solvent, in general. The reaction time is from several hours to several times ten hours. Further, the reaction temperature and time employed in the condensation reaction with halogen compound (V) are 50°-80° C. and 30 minutes to 3 hours. In the above manner, a desired compound can be obtained in a satisfactory yield.

A number of examples of the starting materials employed in practicing the present invention, i.e. thionoamidates (II), alkali hydrosulfides (III), and halogen compounds (V), are shown below, but it is needless to say that these are not limitative.

Thionoamidates:

- O,O-Dimethyl-phosphorothioamidate
- O,O-Diethyl-phosphorothioamidate
- O,O-Di-n-propyl-phosphorothioamidate
- O,O-Di-iso-propyl-phosphorothioamidate
- O,O-Di-n-butyl-phosphorothioamidate
- O,O-Diethyl-N-phenyl-phosphorothioamidate
- O,O-Diethyl-N-benzyl-phosphorothioamidate
- O,O-Diethyl-N-cyclohexyl-phosphorothioamidate
- O,O-Diethyl-N-n-butyl-phosphorothioamidate
- O,O-Diethyl-N-n-propyl-phosphorothioamidate
- O,O-diethyl-N-ethyl-phosphorothioamidate
- O,O-diethyl-N-methyl-phosphorothioamidate
- O,O-Diethyl-N,N-diethyl-phosphorothioamidate
- O,O-Dimethyl-N-n-propyl-phosphorothioamidate
- O,O-Dimethyl-N-n-butyl-phosphorothioamidate
- O,O-Dimethyl-N-phenyl-phosphorothioamidate
- O,O-Dimethyl-N,N-diethyl-phosphorothioamidate
- O,O-Dimethyl-N-iso-propyl-phosphorothioamidate
- O,O-Dimethyl-N,N-dimethyl-phosphorothioamidate
- O,O-Dimethyl-N-allyl-phosphorothioamidate
- O,O-Dimethyl-N,N-diallyl-phosphorothioamidate
- O,O-dimethyl-N-allyl-phosphorothioamidate
- O,O-Diethyl-N,N-diallyl-phosphorothioamidate

Hydrosulfides:**Sodium hydrosulfide****Potassium hydrosulfide****Halogen compounds:**

- 1,3-Diethylthio-2-chloropropane
 1,3-Di-n-propylthio-2-chloropropane
 1-ethylthio-3-ethoxy-2-chloropropane
 1-ethylthio-3-methoxy-2-chloropropane
 1-iso-Propylthio-3-n-propoxy-2-chloropropane
 1-iso-Propylthio-3-methoxy-2-chloropropane
 1-Methylthio-3-methoxy-2-chloropropane
 1-Methylthio-3-iso-propoxy-2-chloropropane
 1-n-Butylthio-3-methoxy-2-chloropropane
 1-Ethylthio-3-n-propoxy-2-chloropropane
 1-Ethylthio-3-iso-propoxy-2-chloropropane

A number of examples of typical phosphorothioamides in accordance with the present invention are shown below.

In practical application, the present compounds may be used singly without the addition of other ingredients or, for easier application of the compounds as controlling chemicals, they may be used in admixture with carriers. Ordinarily, the present compounds are formulated into any optional forms such as emulsifiable concentrates, wettable powders, oil sprays, dusts, irrigants, seed-coating powders, granules, aerosols, fumigants, etc., according to processes thoroughly known to those skilled in the art without necessitating any special conditions, like in the case of common organophosphorus chemicals, and can be made into any desired forms by use of carriers and may be used for any desired purposes. Further, they may be used in admixture with one or more of other chemicals to make the effects thereof broader and higher. For example, they can be used in admixture with organo-phosphorus type insecticides such as O,O-dimethyl O-(3-methyl-4-nitrophenyl)phosphorothioate, O,O-dimethyl S-(N-methylcarbamoyl)methyl phosphorothioate, etc.; pyrethroid type insecticides such as Allethrin, phthalathrin, etc.; organochlorine type insecticides such as BHC, DDT, etc.; carbamate type insecticides such as 3,4-dimethylphenyl-N-methylcarbamate, 1-naphthyl-N-methylcarbamate, etc.; organo-sulfur type fungicides such as pentachlorobenzyl alcohol, pentachlorobenzaldoxime, etc.; and organo-arsenic type fungicides. Further, they are easily miscible with herbicides, fertilizers, plant growth-controlling agents, synergists, attractants, repellents and the like chemicals to give multi-purpose compositions and, depending on combinations, synergistic effects can be expected.

In order to clarify the excellent characteristics and effects of the present compounds, typical test results are shown below with reference to test examples. In the test examples, the numerals in the parentheses represent the numbers of the present compounds exemplified before.

Test Example 1

A mottled kidney bean plant at the 2 leaves stage, which had elapsed 20 days after sowing, was parasitized with a large number of adults of two-spotted red spider mites (*Tetranychus telarius*). The leaves of the kidney bean plant parasitized with said mites were immersed for 1 minute in an aqueous dilute solution of each of the present compounds in the form of wettable powders, and water was fed so as not to wither the leaves. After 48 hours, the alive and dead of the spider mites were observed by means of a magnifying glass and, from the mortality, LC50 values were calculated according to Finney's simplified iconography to obtain the results set forth in Table 1.

TABLE 1

Compound No.	LC50 (times)
(3)	540,000
(5)	460,000
(6)	660,000
(7)	200,000

*Registered trade name for an insecticide produced by Geigy Co.

Test Example 2

Insecticidal effects on smaller brown planthoppers: air-drying.

A rice seedling (height 15-20 cm), which had elapsed 15 days after germination, was immersed for 1 minute in an aqueous dilute emulsion at a given concentration of each of the present compounds in the form of emulsifiable concentrates. After air-drying the rice seedling was put in a large test tube. Into the test tube were liberated 20-30 smaller brown planthoppers, and the tube was covered with gauze. After 24 hours, the alive and dead of the planthoppers were observed

and, from the mortality, LC50 values were calculated according to Finney's iconograph to obtain the results as set forth in Table 2.

Test Example 4

A mottled kidney bean plant was grown to the 2 leaves stage in a flower pot of 9 cm. in diameter. The root portion of the plant was sprinkled with 6 Kg/10 ares of each of the present compounds in the form of 3 percent granules. At the same time, the leaves of the plant were parasitized with a large number of two-spotted red spider mite adults. After 72 hours, the leaves were cut and taken up, and the alive and dead of the mites were observed by means of a magnifying glass to obtain the results as set forth in Table 4.

40 Test Example 14

Preventive effects on rice blast:

A rice plant (variety: Waseasahi), which had been cultivated to the 3 leaves stage in a flower pot of 9 cm in diameter, was sprayed with 7 ml/pot of a given concentration emulsion of each of test chemicals in the form of emulsifiable concentrates. After 1 day, the plant was sprayed and inoculated with a spore suspension of rice blast fungus. 4 Days thereafter, the number of spots generated was counted to investigate the fungicidal effects of the test chemicals, whereby the results as set forth in Table 14 were obtained.

Compound No.	TABLE 14	
	Active ingredient concentration (p.p.m.)	Preventive value
(9)	500	93.6
(11)	500	100.0

O,O-diisopropyl S-benzyl phosphorothioate *	500	88.1
Nontreatment	—	0

*Control; trade name for a fungicide of Kumiai Chemical Co.

70 Preventive value was calculated according to the following equation:

$$\text{Preventive value} = \frac{\text{Number of spots in nontreated area} - \text{Number of spots in treated area}}{\text{Number of spots in nontreated area}} \times 100$$

75 Test Example 15

A mottled kidney bean plant at the 2 leaves stage, which had elapsed 20 days after sowing, was parasitized with a large number of adults of two-spotted red spider mites (*Tetranychus telarius*). The leaves of the kidney bean plants parasitized with said mites were immersed for 1 minute in an aqueous dilute solution of each of the present compounds in the form of wettable powders, and water was fed so as not to wither the leaves. After 48 hours, the alive and dead of the spider mites were observed by means of a magnifying glass and, from the mortality, LC50 values were calculated according to Finney's simplified iconography to obtain the results as set forth in Table 15.

Procedures for the preparation of the present compounds and for the formulation of the present compositions are illustrated below with reference to examples, but it is needless to say that the present invention is not limited only to these.

Example 1

Formulation of emulsifiable concentrates:

Each of the compounds set forth in the table below was thoroughly mixed successively with given proportions of the solvent and emulsifier shown in the table to obtain a homogeneous emulsifiable concentrate. In application, the concentrate was diluted with water and the resulting emulsion was sprayed.

Active ingredient (%)	Solvent (%)	Emulsifier (%)
Compound (1) 50	Xylene 30	*Sorpol 2020 20
Compound (3) 20	Cyclohexanone 50	*Sorpol 2492 30

*Sorpol: Registered trade name for an emulsifier produced by Toho Chemical Co.

Example 2

Formulation of wettable powders:

40 Parts of the compound (5) and 5 parts of Sorpol 5029 (registered trade name for an emulsifier produced by Toho Chemical Co.) were thoroughly mixed together. This mixture was kneaded, while being dropped, with 55 parts of 200 mesh talc, which was under thorough stirring in a mortar, whereby a wettable powder was obtained. In application, the powder was diluted with water and the resulting solution was sprayed.

Example 3

Formulation of dusts:

In such proportion as shown in the table below, each of the compounds set forth in the table was dissolved in a small amount of acetone, and the solution was thoroughly mixed with 200 mesh talc. Thereafter, the acetone was removed by vaporization to obtain a dust of each compound. In application, the dust was dusted as it was.

10 Active ingredient (%)

Extender (%)

Compound (3) 2	Talc 98
Compound (6) 4	Talc 96

15

Example 4

Formulation of granules:

In such proportion as shown in the table below, each of the present compounds was mixed with the binder and extender in the order set forth in the table. This mixture was kneaded with a small amount of water, was granulated by means of a granulator and was then dried to obtain a granule. In application, the granule was sprinkled as it was.

Compound (4) 2	Sodium lignin sulfonate 1	Clay 97
Compound (7) 5	Sodium lignin sulfonate 2	Clay 93

Example 5

Preparation of compound (1):

Into a solution of 5.6 g. of potassium hydroxide in 50 ml. of ethyl alcohol was dropped at room temperature 16.9 g. of O,O-diethyl-phosphorothiooamidate, and the mixture was refluxed with stirring for 8 hours. Subsequently, 19.9 g. of 1,3-diethylthio-2-chloropropane was further dropped into the mixture at 40°-50° C. over a period of 30 minutes, and the resulting mixture was refluxed with stirring for 2 hours. After removing the solvent by distillation, the residue was charged with toluene, was washed with 5 percent sodium carbonate and then with water, and was dried over anhydrous sodium sulfate. Thereafter, the toluene was removed by distillation under reduced pressure to obtain 25.8 g. of yellow oily O-ethyl-S-(2-ethylthio-1-ethylthiomethyl)-ethyl-phosphorothioamidate, $n_D^{21.5}$ 1.5147.

S		31.70	31.54
N		4.61	4.33

Example 6

Preparation of compound (2):

5.6 g. of potassium hydroxide was reacted with 16.9 g. of O,O-diethyl-thionoamidate in entirely the same manner as in Example 5. Into the reaction liquid was dropped at room temperature over a period of 15 minutes 18.3 g. of 1-ethylthio-3-ethoxy-2-chloropropane, and the mixture was refluxed with stirring for 3 hours. Thereafter, the same treatments as in Example 5 were effected to obtain 23.3 g. of a pale yellow oily O-ethyl-S-(2-ethylthio-1-ethoxymethyl)ethyl-phosphorothioamidate, $n_D^{21.5}$ 1.5148.

75 Example 7

Preparation of compound (3):

Into a solution of 8.0 g. of sodium hydroxide in 100 ml. of ethyl alcohol was dropped at room temperature over a period of 30 minutes 28.2 g. of O,O-dimethyl-phosphorothiooamidate, and the mixture was refluxed with stirring for 5 hours. After removing the methyl alcohol by distillation under reduced pressure, a crystal deposited was suspended in ethyl ether, and the suspension was filtered to obtain 28.3 g. of a white crystal of sodium O-methyl-phosphorothiooamidate.

14.9 g. of this crystal was dissolved in 50 ml. of methyl alcohol and was charged with 16.9 g. of 1-ethylthio-3-methoxy-2-chloropropane, and the mixture was refluxed with stirring for 3 hours. Thereafter, the same treatments as in Example 5 were effected to obtain 23.0 g. of pale yellow oily O-methyl-S-(2-ethylthio-1-methoxymethyl)-ethyl-phosphorothiooamidate, n_D^{20} 1.5125.

Example 13

Formulation of wettable powder:

40 Parts of the compound (3) and 5 parts of Sorpol 5029 (registered trade name for an emulsifier produced by Toho Chemical Co.) were thoroughly mixed together. This mixture was kneaded, while being mixed, with 55 parts of 200 mesh talc, which was under thorough stirring in a mortar, whereby a wettable powder was obtained. In application, the powder was diluted with water and the resulting solution was sprayed.

Example 14

Formulation of granules:

In such proportions as shown in the table below, each of the present compounds was mixed with the binder and extender in the order described in the table. This mixture was kneaded with a small amount of water, was granulated by means of a granulator and was then dried to obtain a granule. In application, the granule was sprinkled as it was.

Active ingredient (%)	Binder (%)	Extender (%)
Compound (11) 2	Sodium lignin sulfonate 1	Clay 97
Compound (13) 5	Sodium lignin sulfonate 2	Clay 93

Example 15

Formulation of dusts:

In such proportion as shown in the table below, each of the compounds set forth in the table was dissolved in a small amount of acetone, and the solution was thoroughly mixed with 200 mesh talc. Thereafter, the acetone was removed by vaporization to obtain a dust of each compound. In application, the dust was dusted as it was.

Active ingredient (%)	Extender (%)
Compound (9) 2	Talc 98
Compound (12) 4	Talc 96

Example 16

Preparation of compound (8):

A solution of 11.2 g. of potassium hydroxide in 100 ml. of ethyl alcohol was saturated, under cooling, with hydrogen sulfide to prepare an ethyl alcohol solution of potassium hydrosulfide. To this solution was added at room temperature 39.4 g. of O,O-diethyl-N-ethyl-phosphorothiooamidate, and the mixture was refluxed with stirring for 17 hours. After removing the solvent by distillation under reduced pressure, the mixture was charged with acetone to remove insolubles, and then the acetone was removed by distillation under reduced pressure. The residue was dissolved in water and the solution was washed with toluene. From the aqueous layer, water was removed by distillation under reduced pressure to obtain 20.0 g. of a milk-white crystal of wettable potassium O-ethyl-N-ethyl-phosphorothiooamidate.

11.0 g. of this crystal was dissolved in 50 ml. of ethyl alcohol. To this solution was added at room temperature 8.4 g. of 1-ethylthio-3-methoxy-2-chloropropane, and the mixture was refluxed with stirring for 2.5 hours. After removing the solvent by distillation under reduced pressure, the residue was charged with toluene, and was washed with 3 percent sodium hydrogencarbonate and then with water. Thereafter, the toluene was removed by distillation under reduced pressure to obtain 13.5 g. of reddish orange oily O-ethyl-S-(2-ethylthio-1-methoxymethyl)-ethyl-N-ethyl-phosphorothiooamidate, n_D^{21} 1.5080.

N	4.65	4.55	

Example 17

Preparation of compound (9):

An ethyl alcohol solution of potassium hydrosulfide was prepared in the same manner as in Example 16 from 100 ml. of ethyl alcohol, 11.2 g. of potassium hydroxide, and hydrogen sulfide. To the said solution was added 45.0 g. of O,O-diethyl-N,N-diethyl-phosphorothiooamidate, and the mixture was refluxed with stirring for 17 hours. The mixture was treated in the same manner as in Example 16 to obtain 15.1 g. of a milk-white crystal of potassium O-ethyl-N,N-diethyl-phosphorothiooamidate.

12.0 g. of this crystal was mixed with 8.4 g. of 1-ethylthio-3-methoxy-2-chloropropane and 50 ml. of ethyl alcohol, and the mixture was refluxed with stirring for 3 hours. Thereafter, the same treatment as in Example 16 were effected to obtain 14.9 g. of reddish brown oily O-ethyl-S-(2-ethylthio-1-methoxymethyl)-ethyl-N,N-diethyl-phosphorothiooamidate, n_D^{24} 1.4981.

Example 19

Preparation of compound (11):

An ethyl alcohol solution of potassium hydrosulfide was prepared in the same manner as in Example 16 from 100 ml. of ethyl alcohol, 11.2 g. of potassium hydrosulfide, and hydrogen sulfide. To this solution was added 45.0 g. of O,O-diethyl-N-n-butyl-phosphorothiooamidate, and the mixture was refluxed with stirring for 18 hours. Subsequently, the mixture was treated in the same manner as in Example 16 to obtain 23.8 g. of a white crystal of potassium O-ethyl-N-n-butyl-phosphorothiooamidate.

12.0 g. of this crystal was mixed with 9.8 g. of 1-n-butylthio-3-methoxy-2-chloropropane and 50 ml. of ethyl alcohol, and the mixture was refluxed with stirring for 3 hours. Thereafter, the same treatments as in Example 16 were effected to obtain 16.3 g. of yellow oily O-ethyl-S-(2-n-butylthio-1-methoxymethyl)-ethyl-N-n-butyl-phosphorothiooamidate, n_D^{20} 1.4985.

Elementary analysis	$C_{14}H_{32}NO_3PS_2$:	Calculated (%)	Found (%)
P	8.66	8.71	
S	17.94	17.78	
N	3.92	4.05	

Example 20

Preparation of compound (12):

14.0 g. of a white crystal of potassium O-ethyl-N-benzyl-phosphorothiooamidate obtained in the same manner as in Example 16 was mixed with 8.4 g. of 1-ethylthio-3-methoxy-2-chloropropane and 50 ml. of ethyl alcohol, and the mixture was refluxed with stirring for 3 hours. Thereafter, the same treatment as in Example 16 were effected to obtain 16.6 g. of reddish brown oily O-ethyl-S-(2-ethylthio-1-methoxymethyl)-ethyl-N-benzyl-phosphorothiooamidate, n_D^{22} 1.5449.

Elementary analysis	$C_{15}H_{34}NO_3PS_2$:	Calculated (%)	Found (%)
P	8.52	8.41	
S	17.64	17.89	
N	3.85	3.65	

Example 21

Preparation of compound (13):

13.5 g. of a white crystal of O-ethyl-N-cyclohexyl-phosphorothiooamidate obtained in the same manner as in Example 16 was mixed with 8.4 g. of 1-ethylthio-3-methoxy-2-chloropropane and 50 ml. of ethyl alcohol, and the mixture was refluxed with stirring for 3 hours. Thereafter, the same treatments as in Example 16 were effected to obtain 15.4 g. of yellow oily O-ethyl-S-(2-ethylthio-1-methoxymethyl)-ethyl-N-cyclohexyl-phosphorothiooamidate, n_D^{21} 1.5179.

Elementary analysis	$C_{16}H_{36}NO_3PS_2$:	Calculated (%)	Found (%)
P	8.71	8.73	
S	18.04	17.68	
N	3.94	3.97	

Example 22

Preparation of compound (14):

13.0 g. of a yellowish green viscous liquid of potassium O-ethyl-N-phenyl-phosphorothiooamidate obtained in the same manner as in Example 16 was mixed with 8.4 g. of 1-ethylthio-3-methoxy-2-chloropropane and 50 ml. of ethyl alcohol, and the mixture was refluxed with stirring for 3 hours. Thereafter, the same treatments as in example 16 were effected to obtain 15.8 g. of O-ethyl-S-(2-ethylthio-1-methoxymethyl)-ethyl-N-phenyl-phosphorothiooamidate, $n_D^{20.4}$ 1.5558.

Elementary analysis	for $C_{14}H_{34}NO_3PS_2$:	Calculated (%)	Found (%)
P	8.86	9.09	
S	18.35	17.92	
N	4.01	4.23	

Example 23

Preparation of compound (17):

A methyl cellosolve solution of potassium hydrosulfide was prepared in the same manner as in Example 16 from 100 ml. of methyl cellosolve, 11.2 g. of potassium hydroxide, and hydrogen sulfide. To this solution was added 31.0 g. of O,O-dimethyl-N-methyl-phosphorothioamide, and the mixture was stirred at 95° – 100° C. for 4 hours. After removing the solvent by distillation under reduced pressure, the mixture was dissolved in water and the solution was washed with toluene. From the aqueous layer, water was removed by distillation under reduced pressure to obtain quantitatively a white crystal of wettable potassium O-methyl-N-methyl-phosphorothioamide.

9.9 g. of this crystal was mixed with 8.4 g. of 1-ethylthio-3-methoxy-2-chloropropane and 50 ml. of methyl alcohol, and the mixture was refluxed with stirring for 2 hours. Thereafter, the same treatment as in Example 16 were effected to obtain 12.3 g. of yellow oily O-methyl-S-(2-ethylthio-1-methoxymethyl)-ethyl-N-methyl-phosphorothioamide, $n_D^{23.0}$ 1.5160.

Elementary analysis	for $C_9H_{20}NO_3PS_2$:	Calculated (%)	Found (%)
P	11.33	11.46	
S	23.45	23.58	
N	5.12	4.92	

Example 24

Preparation of compound (18):

A mixture comprising a white crystal of wettable potassium O-methyl-N-n-propyl-phosphorothioamide obtained in the same manner as in Example 23, 8.4 g. of 1-ethylthio-3-methoxy-2-chloropropane and 50 ml. of methyl alcohol was refluxed with stirring for 2 hours. Thereafter, the same treatments as in Example 16 were effected to obtain 13.4 g. of yellow oily O-methyl-S-(2-ethylthio-1-methoxymethyl)-ethyl-N-n-propyl-phosphorothioamide, $n_D^{20.5}$ 1.5920.

Elementary analysis	for $C_{10}H_{22}NO_3PS_2$:	Calculated (%)	Found (%)
P	10.28	10.12	
S	21.28	20.79	
N	4.65	4.51	

Example 25

Preparation of compound (27):

A mixture comprising 11.4 g. of potassium O-methyl-N-n-propyl-phosphorothioamide, 7.7 g. of 1-methylthio-3-methoxy-2-chloropropane and 50 ml. of methyl alcohol was refluxed with stirring for 2 hours. Thereafter, the same treatments as in Example 16 were effected to obtain 13.3 g. of yellow oily O-methyl-S-(2-methylthio-1-methoxymethyl)-ethyl-N-n-propyl-phosphorothioamide, $n_D^{28.5}$ 1.5067.

Elementary analysis	for $C_9H_{22}NO_3PS_2$:	Calculated (%)	Found (%)
P	10.78	10.72	
S	22.31	21.94	
N	4.87	4.80	

Example 26

Preparation of compound (19):

A mixture comprising 11.4 g. of a white crystal of wettable potassium O-methyl-N-iso-propyl-phosphorothioamide obtained in the same manner as in Example 23, 8.4 g. of 1-ethylthio-3-methoxy-2-chloropropane and 50 ml. of methyl alcohol was refluxed with stirring for 2 hours. Thereafter, the same treatments as in Example 16 were effected to obtain 13.7 g. of yellow oily O-methyl-S-(2-ethylthio-1-methox-

ymethyl)-ethyl-N-iso-propyl-phosphorothioamide, $n_D^{21.8}$ 1.5072.

Elementary analysis	for $C_{10}H_{24}NO_3PS_2$:	Calculated (%)	Found (%)
P	10.28	9.97	
S	21.28	21.06	
N	4.65	4.38	

Example 27

Preparation of compound (20):

A mixture comprising 12.1 g. of a white crystal of wettable potassium O-methyl-N-n-butyl-phosphorothioamide obtained in the same manner as in Example 23, 8.4 g. of 1-ethylthio-3-methoxy-2-chloropropane and 50 ml. of methyl alcohol was refluxed with stirring for 2 hours. Thereafter, the same treatments as in Example 16 were effected to obtain 14.4 g. of yellow oily O-methyl-S-(2-ethylthio-1-methoxymethyl)-ethyl-N-n-butyl-phosphorothioamide, $n_D^{23.5}$ 1.5050.

Elementary analysis	for $C_{11}H_{26}NO_3PS_2$:	Calculated (%)	Found (%)
P	9.82	9.80	
S	20.33	19.84	
N	4.44	4.40	

Example 28

Preparation of compound (21):

A methyl cellosolve solution of potassium hydrosulfide was prepared in the same manner as in Example 16 from 100 ml. of methyl cellosolve, 11.2 g. of potassium hydroxide, and hydrogen sulfide. To this solution was added 36.7 g. of O,O-diethyl-N-methyl-phosphorothioamide, and the mixture was stirred at 95° – 100° C. for 6 hours. Subsequently, the mixture was treated in the same manner as in Example 16 to obtain 30.9 g. of a white crystal of wettable potassium O-ethyl-N-methyl-phosphorothioamide.

10.6 g. of this crystal was mixed with 8.4 g. of 1-ethylthio-3-methoxy-2-chloropropane and 50 ml. of ethyl alcohol, and the mixture was refluxed with stirring for 2 hours. Thereafter, the same treatments as in Example 16 were effected to obtain 13.3 g. of yellow oily O-ethyl-S-(2-ethylthio-1-methoxymethyl)-ethyl-N-methyl-phosphorothioamide, $n_D^{24.5}$ 1.5121.

Elementary analysis	for $C_9H_{22}NO_3PS_2$:	Calculated (%)	Found (%)
P	10.78	10.58	
S	22.31	22.47	
N	4.87	4.64	

Example 29

Preparation of compound (24):

A mixture comprising 10.6 g. of potassium O-ethyl-N-methyl-phosphorothioamide, 7.7 g. of 1-methylthio-3-methoxy-2-chloropropane and 50 ml. of ethyl alcohol was refluxed with stirring for 2 hours. Thereafter, the same treatments as in Example 16 were effected to obtain 12.9 g. of pale yellow oily O-ethyl-S-(2-methylthio-1-methoxymethyl)-ethyl-N-methyl-phosphorothioamide, $n_D^{26.0}$ 1.5097.

Elementary analysis	for $C_9H_{22}NO_3PS_2$:	Calculated (%)	Found (%)
P	11.33	10.98	
S	23.45	23.00	
N	5.12	5.08	

Example 30

Preparation of compound (25):

A mixture comprising 10.6 g. of potassium O-ethyl-N-methyl-phosphorothioamide, 9.1 g. of 1-isopropylthio-3-methoxy-2-chloropropane and 50 ml. of ethyl alcohol was refluxed with stirring for 2 hours. Thereafter, the same treatments as in Example 16 were effected to obtain 13.2 g. of pale yellowish green oily O-ethyl-S-(2-isopropylthio-1-methox-

ymethyl)-ethyl-N-methyl-phosphorothioamidate, 1.5048.

Elementary analysis	for $C_{10}H_{24}NO_3PS_2$:	Calculated (%)	Found (%)
P	10.31	10.01	
S	21.35	21.09	
N	4.66	4.59	

Example 31

Preparation of compound (26):

A mixture comprising 10.6 g. of potassium O-ethyl-N-methyl-phosphorothioamidate, 9.8 g. of 1-ethylthio-3-isopropoxy-2-chloropropane and 50 ml. of ethyl alcohol was refluxed with stirring for 2 hours. Thereafter, the same treatments as in Example 16 were effected to obtain 13.9 g. of O-ethyl-S-(2-ethylthio-1-isopropoxy)-ethyl-N-methyl-phosphorothioamidate, $n_D^{25.0}$ 1.4981.

Elementary analysis	for $C_{11}H_{26}NO_3PS_2$:	Calculated (%)	Found (%)
P	9.82	9.62	
S	20.33	20.36	
N	4.44	4.20	

Example 32

Preparation of compound (22):

A mixture comprising 12.1 g. of a white crystal of wettable potassium O-ethyl-N-isopropyl-phosphorothioamidate obtained in the same manner as in Example 28, 8.4 g. of 1-ethylthio-3-methoxy-2-chloropropane and 50 ml. of ethyl alcohol was refluxed with stirring for 2 hours. Thereafter, the same treatments as in Example 16, were effected to obtain 14.5 g. of pale yellow oily O-ethyl-S-(2-ethylthio-1-methoxy-methyl)-ethyl-N-isopropyl-phosphorothioamidate, $n_D^{21.5}$ 1.5020.

Elementary analysis	for $C_{11}H_{26}NO_3PS_2$:	Calculated (%)	Found (%)
P	9.82	9.72	
S	20.33	19.95	
N	4.44	4.06	

Example 33

Preparation of compound (23):

A mixture comprising 12.9 g. of a white crystal of wettable potassium O-ethyl-N-sec-butyl-phosphorothioamidate, 8.4 g. of 1-ethylthio-3-methoxy-2-chloropropane and 50 ml. of ethyl alcohol was refluxed with stirring for 2 hours. Thereafter, the same treatments as in Example 16 were effected to obtain 15.2 g. of yellow oily O-ethyl-S-(2-ethylthio-1-methoxy-methyl)-ethyl-N-sec-butyl-phosphorothioamidate, $n_D^{28.5}$ 1.4992.

Elementary analysis	for $C_{12}H_{28}NO_3PS_2$:	Calculated (%)	Found (%)
P	9.40	9.32	
S	19.46	19.35	
N	4.25	4.09	

Example 34

Formulation of emulsifiable concentrates:

Each of the compounds set forth in the table below was thoroughly mixed successively with the solvent and emulsifier in such proportions as shown in the table to obtain a dust. In application, each dust was dusted as it was.

Active ingredient (%)	Solvent (%)	Emulsifier (%)
Compound (28) 50	Xylene 30	*Sorpol 2020 20
Compound (30) 20	Cyclohexanone 50	*Sorpol 2492 30

*Registered trade name for an emulsifier produced by Toho Chemical Co.

Example 35

Formulation of wettable powder:

40 Parts of the compound (30) was thoroughly mixed with 5 parts of Sorpol 5029 (registered trade name for an emulsifier produced by Toho Chemical Co.). This mixture was kneaded, while being dropped, with 55 parts of 200 mesh talc, which was under thorough stirring in a mortar, to obtain a wettable powder. In application, the powder was diluted with water, and the solution was sprayed.

Example 36

Formulation of granules:

In such proportions as set forth in the table below, each of the compounds shown in the table was mixed with the binder and emulsifier in this order. Subsequently, the mixture was kneaded with a small amount of water, was granulated by means of a granulator and was then dried to obtain a granule. In application, the granule was sprinkled as it was.

	Active ingredient (%)	Binder (%)	Extender (%)
20	Compound (28) 2	Sodium lignin sulfonate 1	Clay 97
	Compound (29) 5	Sodium lignin sulfonate 2	Clay 93

25

Example 37

Formulation of dust:

In such a proportion as set forth in the table below, the present compound (30) was dissolved in a small amount of acetone, and the solution was thoroughly mixed with 200 mesh talc. Thereafter, the acetone was removed by vaporization to obtain a dust. In application, the dust was dusted as it was.

	Active ingredient (%)	Extender (%)
30	Compound (30) 2	Talc 98

40

Example 38

Preparation of compound (28):

A solution of 11.2 g. of potassium hydroxide in 100 ml. of methyl cellosolve was saturated, under cooling, with hydrogen sulfide to prepare a methyl cellosolve solution of potassium hydrosulfide. To this solution was added at room temperature 36.2 g. of O,O-dimethyl-N-allyl-phosphorothioamidate, and the mixture was stirred at 95° 14 100° C. for 5 hours. After removing the solvent by distillation under reduced pressure, the mixture was charged with acetone to remove insolubles, and then the acetone was removed by distillation under reduced pressure. Subsequently, the residue was dissolved in water, and the solution was washed with toluene. From the aqueous layer, water was removed by distillation under reduced pressure to obtain 40.9 g. of a white crystal of wettable potassium O-methyl-N-allyl-phosphorothioamidate.

11.3 g. of this crystal was dissolved in 50 ml. of methyl alcohol and was charged with 8.4 g. of 1-ethylthio-3-methoxy-2-chloropropane, and the mixture was refluxed with stirring for 2 hours. After removing the solvent by distillation under reduced pressure, the residue was charged with water and chloroform, and the chloroform layer was dried over anhydrous sodium sulfate. Thereafter, the chloroform was removed by distillation under reduced pressure to obtain 13.7 g. of yellow oily O-methyl-S-(2-ethylthio-1-methoxyethyl)-ethyl-N-allyl-phosphorothioamidate, $n_D^{28.0}$ 1.5180.

70	Elementary analysis	for $C_{12}H_{28}NO_3PS_2$:	Calculated (%)	Found (%)
	P	10.35	10.36	
	S	21.42	21.71	
	N	4.68	4.86	

Example 39
Preparation of compound (29):

A mixture comprising 11.3 g. of potassium O-methyl-N-allyl-phosphorothiooamidate, 7.7 g. of 1-methylthio-3-methoxy-2-chloropropane and 50 ml. of methyl alcohol was refluxed with stirring for 2 hours. Thereafter, the same treatments as in Example 38 were effected to obtain 12.4 g. of yellow oily O-methyl-S-(2-methylthio-1-methoxymethyl)-ethyl-N-allyl-phosphorothiooamidate, $n_D^{21.0}$ 1.5193.

Elementary analysis	for $C_9H_{18}NO_3PS_2$:
Calculated (%)	Found (%)
P 10.85	10.74
S 22.47	21.96
N 4.91	4.70

Example 40

Preparation of compound (30):

A mixture comprising 12.0 g. of a white crystal of wettable potassium O-ethyl-N-allyl-phosphorothiooamidate obtained in the same manner as in Example 38, 8.4 g. of 1-ethylthio-3-methoxy-2-chloropropane and 50 ml. of ethyl alcohol was refluxed with stirring for 2 hours. Thereafter, the same treatments as in Example 38 were effected to obtain 14.9 g. of yellow oily O-ethyl-S-(2-ethylthio-1-methoxy-ethyl)-ethyl-N-allyl-phosphorothiooamidate, $n_D^{21.5}$ 1.5104.

Calculated (%)	Found (%)
P 9.88	9.53
S 20.46	20.77
N 4.47	4.31

Example 41

Preparation of compound (31):

A methyl cellosolve solution of potassium hydrosulfide was prepared from 100 ml. of methyl cellosolve, 11.2 g. of potassium hydroxide, and hydrogen sulfide. To this solution was added 44.2 g. of O,O-dimethyl-N,N-diallylphosphorothiooamidate, and the mixture was stirred at 95°-100bL C. for 4 hours. Subsequently, the mixture was treated in the same manner as in Example 38 to obtain 48.7 g. of wettable white crystalline potassium O-methyl-N,N-diallylphosphorothiooamidate.

13.5 g. of this salt was mixed with 8.4 g. of 1-ethylthio-3-methoxy-2-chloropropane and 50 ml. of methyl alcohol, and the mixture was stirred at 60°-65° C. for 2 hours. Thereafter, the same treatment as in Example 38 were effected to obtain 45 14.3 g. of yellow oily O-methyl-S-(2-ethylthio-1-methoxymethyl)-ethyl-N,N-diallyl-phosphorothiooamidate, $n_D^{21.0}$ 1.5090.

Elementary analysis	for $C_{13}H_{26}NO_3PS_2$:
Calculated (%)	Found (%)
P 9.12	8.93
S 18.89	18.71
N 4.13	4.13

24

What we claim is:

1. A phosphorothiooamidate having the formula,

wherein R_1 is alkyl having up to 4 carbon atoms, R_2 and R_3 are individually hydrogen, alkyl having up to 10 carbon atoms, cyclohexyl, phenyl, aralkyl having up to eight carbon atoms or an alkenyl having up to five carbon atoms, R_4 and R_5 are each alkyl having up to five carbon atoms, and X is oxygen or sulfur.

10 15 2. A phosphorothiooamidate according to claim 1, wherein R_2 and R_3 are hydrogen.

3. A phosphorothiooamidate according to claim 1, wherein R_2 and R_3 are individually hydrogen alkyl having up to 10 carbon atoms, cyclohexyl phenyl or aralkyl having up to eight carbon atoms, and are not hydrogen simultaneously.

20 4. A phosphorothiooamidate according to claim 1, wherein R_2 and R_3 are individually hydrogen or alkenyl having up to five carbon atoms and are not hydrogen simultaneously.

5. A compound of the formula

25 30 6. A compound of the formula

7. A compound of the formula

8. A compound of the formula

9. A compound of the formula

UNITED STATES PATENT OFFICE
CERTIFICATE OF CORRECTION

Patent No. 3,670,057 Dated June 13, 1972

Inventor(s) Hiroshi Tsuchiya et al.

It is certified that error appears in the above-identified patent and that said Letters Patent are hereby corrected as shown below:

Please insert the following missing claim for priority:

--Japanese No. 82964/68 filed November 12, 1968;
Japanese No. 95735/68 filed December 25, 1968;
Japanese No. 82124/69 filed October 13, 1969--

Signed and sealed this 6th day of February 1973.
